(21) Appl. No.: 29/240,164

(22) Filed: Oct. 7, 2005

CLAIM

(51) LOC (8) Cl. 30-99

The ornamental design for a disposable collapsible cat litter tray, as shown and described.

(52) U.S. Cl. D30/161

DESCRIPTION

(58) Field of Classification Search D30/108, D30/110-112, 117-119, 161; 119/28.5, 161-170, 119/482, 496, 499

FIG. 1 is a front perspective view of the disposable collapsible cat litter tray in a partially collapsed position showing a removable front portion for the doorway in dashed lines; FIG. 2 is a rear perspective view thereof;

See application file for complete search history.

FIG. 3 is a top view thereof;
